CLAIM

The ornamental design for a tablet stand assembly, as shown and described.

DESCRIPTION

FIG. 1 is a first perspective view of a tablet stand assembly showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of the tablet stand assembly in a state of use; and,

FIG. 10 is front perspective view thereof.

The broken lines shown in the drawings depict portions of the tablet stand assembly that form no part of the claimed design. The evenly spaced broken lines depicting an elec-

(Continued)

tronic device in FIGS. 9 and 10 depict environmental subject matter and forms no part of the claimed design.
